James K. Ross

UNITED STATES PATENT OFFICE.

JAMES K. ROSS, OF LEBANON, OHIO.

FIREPLACE.

Specification of Letters Patent No. 27,741, dated April 3, 1860.

To all whom it may concern:

Be it known that I, JAMES K. Ross, of Lebanon, Warren County, Ohio, have invented a certain new and useful Improvement 5 in Fireplaces; and I do hereby declare the following to be a full, clear, and exact description of the same, reference being had to the accompanying drawings, making part of this specification.

10 My improvement in connection with a customary open fire place of a system of passages, &c., for the purpose of supplying apartments with properly warmed and moistened fresh air.

15 In the accompanying drawing A, B, are two apartments—one of which contains an open iron fire place or box C of which a rear portion only is represented. The upper part of this fire box communicates with a tubular 20 metallic chimney e. The fire box C is set a little in front of the back wall D, and its sides converge slightly away from the jambs E so as to form in the rear of the fire box a chamber F for heating air admitted from 25 without through a grated inlet G.

H is a deflecting plate, which compels the air to first descend to the bottom of the chamber F.

I are water vessels placed in contact with 30 the fire box.

J is a feed cock and K is a door through which to replenish the vessels I with water. The door K may also serve as a man hole for cleansing or repairing the chamber F.

L are pipes by which any desired portion 35 of the air may be conducted to one or more apartments B.

M M' are registered apertures by which the heated and moistened fresh air may be admitted at desired places and quantities. 40 N is a damper, by which the air entrance may be contracted or closed at will. The same passages may be used very advantageously for summer and nocturnal ventilation.

45 I claim as new and of my invention herein and desire to secure by Letters Patent—

The arrangement in the rear of an open fire place C of a heating chamber F, vaporizing apparatus I J K and registered communication G N L M M' with both the external and the internal air as and for the purposes set forth.

In testimony of which invention, I hereunto set my hand.

JAMES K. ROSS.
